W. E. HUGHES.

BRUSH.

APPLICATION FILED SEPT. 12, 1919.

1,350,652.

Patented Aug. 24, 1920.

Inventor
W. E. Hughes.

By *A. Randolph Jr.*
Attorney.

UNITED STATES PATENT OFFICE.

WILLIAM E. HUGHES, OF GREENVILLE, SOUTH CAROLINA, ASSIGNOR TO ROBERT O. BROOKS, OF ATLANTA, GEORGIA.

BRUSH.

1,350,652.

Specification of Letters Patent. Patented Aug. 24, 1920.

Application filed September 12, 1919. Serial No. 323,287.

To all whom it may concern:

Be it known that I, WILLIAM E. HUGHES, a citizen of the United States, residing at Greenville, in the county of Greenville and State of South Carolina, have invented certain new and useful Improvements in Brushes; and I do hereby declare the following to be a full, clear, and exact description of the invention, such as will enable others skilled in the art to which it appertains to make and use the same.

This invention relates to new and useful improvements in brushes and more particularly to devices for attaching screw threaded handles to brush heads and has for one of its objects the provision of means which will reinforce and strengthen the brush head at its point of connection to the handle as well as firmly attaching the handle to the head and also permits of the inclination of the handle in respect to the head to be reversed so that the reverse use of the brush can be obtained to cause even wearing of said brush.

Another object of this invention is the provision of a brush of the above stated character, which shall be simple, durable and efficient, and which may be manufactured and sold at a comparatively low cost.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawing in which:—

Figure 1 is a perspective view of a brush constructed in accordance with my invention,

Fig. 2 is a transverse sectional view of the same,

Fig. 3 is a perspective of one of said members,

Fig. 4 is an end view of one of the members.

Referring in detail to the drawing, the numeral 1 indicates a brush head having the usual bristles 2. The brush head 1 has a raised or enlarged portion 2 formed upon

its top face at a point intermediate its ends and which is provided with inwardly directed converging openings 3. Transversely curved attaching plates 4 are arranged on the enlarged portion 2 of the head 1 so that one of their edges abut each other while their other edges are disposed on the front 55 and rear faces of the head 1. The attaching plates are secured to the head 1 by fasteners 5 and are adapted to strengthen and reinforce the head at the enlarged portion 60 2. The plates 4 have formed thereon internally screw threaded cylindrical members 6 which project beyond each face of the plates and are arranged in an inclined plane in relation to the plates so as to fit within the openings 3 of the enlarged portion 2 of the 65 head 1. The inner ends of the members 6 project a considerable distance beyond the inner faces of the plates 4 so that they extend a considerable distance into the openings 3 for reinforcing said openings and 70 preventing them from becoming worn or mutilated during the use of the brush. The outer ends of the members 6 project a slight distance beyond the outer faces of the plates 4 so that the screw threaded ends 7 of the 75 handle 8 can be readily turned into the members 6 for firmly connecting the handle to the head 1. The double use of the members 6 permits the reversing of the handle on the brush head 1, that is, the inclination 80 of the handle in respect to the head 1 can be reversed whenever desired. This being 85 principally desirable during the use of the brush to cause the same to wear evenly.

While I have shown and described the 90 preferred embodiment of my invention, it will be understood that minor changes in construction, combination and arrangement of parts may be made without departing from the spirit and scope of the invention 95 as claimed.

Having thus described my invention, what I claim is:—

In combination, a brush head having an enlargement formed intermediate its ends 100 and inwardly directed converging openings formed therein and in communication with each other, transversely curved plates secured to the enlargement and having their opposing ends in abutting engagement and 105 their other ends terminating on the front

and rear walls of the head, and tubular internally screw threaded members formed integrally with the plates and projecting slightly beyond the outer faces of said plates 5 to receive a handle, said members being disposed on converging planes and projecting beyond the inner faces of said plates and extending into and terminating adjacent the

inner ends of the openings to prevent wear on the openings by the handle.

In testimony whereof I affix my signature 10 in presence of two witnesses.

WILLIAM E. HUGHES.
